(57) **CLAIM**

The ornamental design for a manikin head for wall mount, as shown and described.

DESCRIPTION

FIG. 1 is a top plan view of a manikin head showing my design;

FIG. 2 is a bottom plan view thereof;

FIG. 3 is a right side-elevation view thereof;

FIG. 4 is a left side-elevation view thereof;

FIG. 5 is a front elevation view thereof;

FIG. 6 is a rear elevation view thereof;

FIG. 7 is a perspective view thereof; and,

FIG. 8 is a perspective view showing how the manikin head is mounted to a wall.

Broken lines in FIG. 6 and FIG. 8 show a T-shaped mounting element, a wall and a bracket for the manikin head, and form no part of the claimed design.
